FASTENER FOR BURIAL VAULTS

Filed Feb. 28, 1928

INVENTOR

F. C. King

BY C. B. Birkenbeul

ATTORNEY

UNITED STATES PATENT OFFICE

FRED C. KING, OF PORTLAND, OREGON

FASTENER FOR BURIAL VAULTS

Application filed February 28, 1928. Serial No. 257,633.

This invention relates generally to burial vaults and particularly to all metal self-locking types of vaults.

The first object of this invention is to provide an exceedingly simple and efficient form of burial vault which will be easy to construct and not liable to get out of order.

The second object is to make same impervious to the action of water by having the opening of the vault close to its lower edge and also has for a further object the provision of a unique form of latch mechanism whereby the cover will not only be securely held to the base but will also be prevented from rattling or from undesirable lateral movement.

These and other objects, will become more apparent from the specification following as illustrated in the accompanying drawings, in which:

Figure 1 is a side elevation of the vault with one corner broken away to disclose the base. Figure 2 is a vertical section through the vault taken along the line 2—2 in Figure 1. Figure 3 is an enlarged fragmentary section through the base and cover taken along the line 3—3 in Figure 4. Figure 4 is a side elevation of the portion of the vault shown in Figure 3 taken along the line 4—4. Figure 5 is a detail of the latch withholding element.

Similar numbers of reference refer to similar parts throughout the several views.

Referring in detail to the drawings, the vault consists of three principal parts. Namely, a base, a cover, and a latch mechanism.

Base and latches

The base consists of a horizontal floor 10 having downwardly flanged sides 11 the lower edges of which are outturned to form a flange 12 extending entirely around the base. In the edges 11 of the base are formed openings 13 which pass through the longitudinal side walls 11 secured to the under side of the flange 12. Directly underneath the edge of opening 13 is a spring latch member 14 secured by means of a rivet 15 or in any other convenient manner. The latch 14 is provided with an upwardly curved portion 16 which

turns outwardly through the opening 13 and its outwardly turned portion 17 is backwardly and upwardly turned and secured above the portion 16 by means of a weld 18. The top 19 of the latch 14 is provided with a hole 20 and a similar hole 21 is provided in the floor 10, which holes can be brought into register to receive the shank 21—A of the eye 22 for the purpose of holding the latch in a withdrawn position when desired.

Cover

The cover consists of sides 23 which are jointed by the ends 24 and covered by the somewhat rounding top 25. The lower edges 26 of the sides 23 and the end 24 are inturned to form a flange 27 whose top edge 28 just clears the under side of the projecting portion 29. For shipping purposes the latch 14 is withdrawn by pulling its upper portion inwardly through the opening 13 and inserting the shank 21—A of the eye 22 through the holes 21 and 20 which, of course, must be brought into register. This operation is performed at each latch 14 in order to make it possible to place the cover on the base and remove same at will. If, however, it is desired to secure the cover on the base it is only necessary to withdraw the shanks 21—A and it will permit the latches to move outwardly

so that the next time the cover is put into place it will be securely held on the base. It will be noted that not only is the cover held downwardly but laterally to prevent rattling or other undesirable movements. Inaccuracy in manufacturing is taken care of by the holding latches themselves. If at any time it should be desired to open this vault it is only necessary to gain access to the under side of the base and withdraw the various latches. In such event it would be preferable to insert a wedge or other holding element to prevent each latch from again moving out to a holding position before the cover could be removed.

It is a well known fact that many forms of burial vaults have been constructed in the past in which are employed numerous types of bases and covers and latching mechanisms.

It is, therefore, not intended to cover such devices broadly but only within the limits set forth in the following claims.

I claim:

- 5 1. A latch for burial vaults of the class having a hollow base and having a cover provided with a shoulder along its inner lower edge consisting of a flat spring member secured to the under side of said base and curving upwardly into the hollow portion of said base and extending through the side wall thereof, the end of said spring turning backwardly through the opening of said base and fastening upon itself in a manner that the lower side of the projecting portion of said latch shall lie above the shoulder in said cover, and the top side of said latch shall bear against the under side of the top of said base when said cover is raised, and means for holding said latch in an operative position.
- 10 2. A spring latch for burial vaults of the type having an elevated base member provided with upright sides including an outwardly extending flange projecting from the bottom of said sides, certain of said sides having openings formed therein near the top thereof, said latch consisting of a flat spring secured to the under side of said flange curving inwardly along said base, said inwardly turned end having its tip closed back upon itself in a manner to form a closed catch end and normally projecting through the opening thus formed.
- 15 3. A fastener for burial vaults consisting of a U-shaped flat spring having one cover engaging end closed upon itself and having its opposite end provided with a fastening means for mounting same on the base of a burial vault, and having its closed end provided with a latch for holding said fastener in a retracted position whereby said closed end may project through the side of said base when said latch is released.
